UNITED STATES PATENT OFFICE.

VERNE M. CALKINS, OF CRANSTON, RHODE ISLAND, ASSIGNOR TO SAART BROTHERS COMPANY, A CORPORATION OF RHODE ISLAND.

DESIGN FOR A VANITY CASE.

Application filed June 1, 1926. Serial No. 17,898. Term of patent 3½ years.

To all whom it may concern:

Be it known that I, VERNE M. CALKINS, a citizen of the United States, residing at Cranston, in the county of Providence and State of Rhode Island, have invented a new, original, and ornamental Design for a Vanity Case, of which the following is a specification.

In the accompanying drawings, which form a part of this specification—

Figures 1 and 2 are a front and end elevation respectively of a vanity case showing my new design.

I claim:—

The ornamental design for a vanity case, as shown.

VERNE M. CALKINS.
